UNITED STATES PATENT OFFICE.

DANIEL HILL, OF PORTERVILLE, CALIFORNIA.

SCROLL-DISPLAYING DEVICE.

Application filed January 18, 1926. Serial No. 82,107.

This invention relates to improvements in scroll displaying devices.

The principal object of this invention is to provide means whereby a plurality of scrolls having matter imprinted thereon may be exhibited as desired.

Another object of this invention is to provide means whereby a plurality of scrolls may have the web thereof individually exposed, and to further provide means for automatically unwinding and winding and moving the same from one scroll to the next.

A further object is to provide means whereby both sides of the scroll may be viewed.

A still further object is to produce a device of this character which is mechanically simple, and therefore cheap to manufacture.

Other objects and advantages will be apparent during the course of the following description.

In the accompanying drawings forming a part of this specification, and in which like numerals are employed to designate like parts throughout the same,

Figure I is a front elevation of my device with the front plate removed,

Figure II is a side elevation of my device with the side cut away in order to expose the interior thereof,

Figure III is a front elevation of my device as it would appear when in use,

Figure IV is a perspective view of the main control lever,

Figure V is a fragmentary detail view on an enlarged scale showing the manner of mounting the control lever,

Figure VI is a cross-sectional view showing the driving mechanism,

Figure VII is a fragmentary detail view showing the clutch members,

Figure VIII is a schematic diagram of the electrical circuit, and Figure IX is a cross section of the drum.

In order to present reading matter to the public it has been customary to employ books or cards upon which the matter was printed. These methods are both bulky and require a considerable amount of space.

Further a book cannot be successfully used where it is desired to make a display automatically and where cards are employed the abrasion incident to the handling of the cards results in the same presenting an unsightly appearance after a short period of use.

I have therefore provided in my invention, a cylinder within which are mounted a plurality of scrolls in such a manner that they may be unwound so as to be exposed to view 60 then rotated so that both sides may be seen, then rewound, after which the cylinder is moved in such a manner as to present a new scroll which passes through the same cycle 65 of operation.

In the accompanying drawings wherein for the purpose of illustration is shown a preferred embodiment of my invention, the numeral 5 designates a base, the numeral 6 a casing mounted upon the base 5 and 70 having roller bearings 7 interposed therebetween. Within the casing 6 is positioned a cylinder 8 having a plurality of shafts 9 extending there-through to each of which shafts is secured one end of a web 11, to 75 the opposite end of which web is attached a weighted bar 12. The cylinder 8 is mounted upon a shaft 13 so as to be rotated thereby.

By now referring to Figure I it will be noted that the shaft 13 has a crank 14 attached thereto, the purpose of which is to permit manual turning of the cylinder 8, when desired. This cylinder is normally adapted to be automatically operated, and by viewing Figure 2 it will be noted that a 80 gear 16 is positioned upon the shaft 13 and is adapted to be contacted by a worm 17 positioned upon the motor shaft 18. This gear 17 is normally out of engagement with the gear 13 and is only engaged therewith 85 periodically, as will be later described.

The shaft 18 is rotated by a motor 19 pivotally mounted in brackets 21. Upon the opposite end of the shaft 18 is positioned a friction disc 22. The free end of the shaft 18 is supported between lugs 23 formed upon an offset arm 24 of a lever 26. This lever is preferably formed integral with the main control lever 27 which is pivoted upon the arcuate-shaped extremity 28 of a stud 29 90 positioned in the support 31. This support is best illustrated in Figure V.

The upper end of the control lever is bifurcated as shown at 32 so as to straddle a collar 33 formed upon a sliding sleeve 34. 105 This sliding sleeve is provided with oppositely inclined faces 36 and 37 which are adapted to be brought into contact with the friction disc 22 so as to be rotated thereby.

The sliding connection between the collar 34 and the shaft 38 is maintained by a key 39. The shaft 38 is mounted in the supports 110

31 and 39 and carries at one end a male clutch member 41 which is adapted to be brought into successive engagement with the female clutch members 42 mounted upon the 5 shafts 9. The opposite end of the clutch 38 is provided with a head 43, slideable in a sleeve 44 within which is positioned a spring 46. The control lever 27 has formed thereon armatures 47 and 48 which are adapted 10 to be attracted by electro-magnets 49 and 51, respectively.

A magnet 52 placed at right angles to the electromagnets 49 and 51 also acts upon the armatures 47 and 48. These three magnets 15 are electrically connected to a common wire 53 which is grounded upon a clock mechanism 54 within which is a plurality of contacts to which the wires 56, 57 and 58 are connected. These wires of course lead 20 to the respective magnets 49, 52 and 51. The clock mechanism 54 is also provided with a shaft 59 upon which is mounted a pulley 61 over which a belt 62 passes. This belt is in turn reeved over a pulley 63 which 25 is fastened to the base 5.

By viewing Figures II and IV, it will be noted that the control lever 27 has an arm 64 extending outwardly therefrom and provided with a finger-piece 66.

30 By viewing Figure III, it will be noted that this lever 64 extends through the face of the casing 6 and is adapted to be moved in slots 67 and 68 as will be hereinafter described.

35 The manner of operating my device is as follows:—

Assuming that the user has a plurality of scrolls which he desires to display, these scrolls may be inserted in the cylinder 8 in 40 any suitable manner, after which the electric switch controlling the motor 19 is turned on, at the same time the clock mechanism 54 is started the result being that as the contacts within the clock mechanism 45 make and break their respective circuits the pulling tension, assuming that all of the scrolls are rolled within the cylinder, should make contact with the contact to the magnet 51 and will pull the armature 48 toward it, thus moving the sleeve 34 in such a manner 50 as to move the inclined face 37 into contact with the friction disc 22. This will cause the shaft 38 to rotate which will transmit motion through the clutch members 41 and 42 to the shaft 9 which is then positioned at 55 the bottom of the cylinder.

The result will be that the web secured to this shaft will be unreeled and carried 60 downwardly upon its bar 12. As soon as the clock mechanism reaches a point where the current is broken to the electromagnet 51, the control lever 27 will return to its normal 65 position thus dis-engaging the friction disc 22 from its engagement with the inclined surface 27. As soon as the clock mechanism

has moved a little further contact will be made so as to deliver current to the electromagnet 49. This will move the armature 47 toward it, thus pulling the control lever so as to move the inclined surface 36 into contact with the disc 32. The shaft 9 will now be caused to rotate in a direction opposite to that previously described, which will cause the web 11 to be rewound onto the cylinder. 75

As soon as the web has been rewound the clock mechanism will have reached a point which will break the circuit to the magnet 51 and the rewinding operation will stop. The clock mechanism will now complete the 80 circuit to the electro-magnet 52 which will rock the control lever 27 in such a manner that the arm 24 will raise the shaft 18 thus bringing the worm 17 into contact with the gear 16. This will result in the cylinder 85 being rotated, which rotation will further assist in the male clutch member 41 moving out of engagement with the female clutch member 42 which was in contact. This is permitted by the sliding of the shaft 38 90 against the tension of the spring 46. Rotation of the cylinder 8 will result in the bringing of a new female clutch member into a position to be engaged by the male clutch member and at this time the clock 95 mechanism will again have broken the circuit to the magnet 52, with the result that the shaft 18 will again drop to its normal position and the same cycle will be repeated 100 for each scroll.

If it is desired to read both sides of the scroll the clock mechanism is further provided with a latch mechanism, not shown, which will intermittently rotate the casing as a whole a half revolution, thus exposing 105 first one side to view and then the opposite side.

The purpose of the lever 64 and finger piece 66 is to provide for manually operating 110 the device if desired.

It is of course understood that this device may be employed in stores as a show-window display or might be employed wherever it is desired to expose reading matter such as in public places, buildings and the 115 like.

It is to be understood that the form of my invention herewith shown and described is to be taken as a preferred example of the same and that various changes relative to 120 the shape, size and arrangement of parts may be resorted to without departing from the spirit of the invention or the scope of the subjoined claims.

Having thus described my invention, I 125 claim:—

1. In a device of the character described, a casing rotatably mounted upon a base, a shaft positioned in said casing, a cylinder positioned on said shaft, a plurality of 130

scrolls positioned within said cylinder and adapted to be unreeled therefrom, and reeled thereonto, a gear positioned on said shaft, a motor positioned within said device, 5 a worm adapted to be rotated by said motor, means for intermittently moving said worm in contact with said gear so as to rotate said cylinder, and means for intermittently reeling and unreeling said scrolls successively.

10 2. In a device of the character described, a casing rotatably mounted upon a base, a shaft positioned in said casing, a cylinder positioned on said shaft, a plurality of scrolls positioned within said cylinder and adapted to be unreeled therefrom, and reeled thereonto, a gear positioned on said shaft, a motor positioned within said device,

a worm adapted to be rotated by said motor, means for intermittently moving said worm in contact with said gear so as to rotate said cylinder, and means for intermittently reeling and unreeling said scrolls successively, 20 said means comprising a friction disc adapted to be rotated by said motor, a sleeve having friction surfaces thereon, a plurality of electro-magnets adapted to move said sleeve so as to cause said friction surfaces to be individually contacted by said friction disc for the purpose of reeling and unreeling said scrolls and a clock mechanism 25 for intermittently completing the electric circuits to said electromagnets.

In testimony whereof I affix my signature.
DANIEL HILL.
